UNITED STATES PATENT OFFICE.

FRANK NEUBERT, OF SPRINGFIELD, MASSACHUSETTS.

DESIGN FOR A BADGE.

SPECIFICATION forming part of Design No. 15,725, dated January 13, 1885.

Application filed September 11, 1884. Term of patent 14 years.

To all whom it may concern:

Be it known that I, FRANK NEUBERT, of Springfield, in the county of Hampden and State of Massachusetts, have invented a new 5 and original Design for Badges, of which the following is a full, clear, and exact description, reference being had to the accompanying drawing, making part of this specification, which fully illustrates the nature of my de-
sign.

The design relates to a badge; and it consists of a flag having knots at the upper part and fringes at the remaining sides, a shield having a central open panel, and side panels orna-
mented with stars and stripes. A wreath of
laurel surrounds the lower part of the shield.

In the accompanying drawing, A represents 15 an American flag, which has fringes at the sides and the lower edge, and knots *a a* at the upper part. On the flag A is a shield, B, that is sur-
rounded at the lower part by a wreath of lau-
rel C. The shield B has at its center a panel,

D, of oval or other shape, for inserting a por-
trait or other emblems. The space around the
central panel, D, is divided by diagonal lines 25
d d into smaller panels, that are filled with
stars and stripes, respectively.

Having thus described my design, I desire to
claim as new and to secure by Letters Patent--

The design for a badge, consisting of a flag 30 having fringed sides and knots at the upper part, a shield on said flag having a central open panel and side panels ornamented with stars and stripes, and a laurel-wreath extending around the lower part of the shield, as shown 35 and described.

In testimony that I claim the foregoing as
my invention I have signed this specification
this 4th day of September, 1884.

FRANK NEUBERT.
